UNITED STATES PATENT OFFICE.

ALPHONS DRYFOOS, OF NEW YORK, N. Y.

DESIGN FOR A BOTTLE.

SPECIFICATION forming part of Design No. 24,500, dated July 23, 1895.

Application filed June 21, 1895. Serial No. 553,608. Term of patent 7 years.

To all whom it may concern:

Be it known that I, ALPHONS DRYFOOS, a citizen of the United States, residing at New York city, in the county and State of New York, have invented and produced a new and original Design for a Bottle, of which the following is a specification, reference being had to the accompanying drawings, forming a part of this specification, in which—

10 Figure 1 is a perspective view of a bottle, showing my design; and Fig. 2 is a sectional plan view of the same on the line 2 2 of Fig. 1.

The leading feature of my design consists in niches A, formed in the wall of the bottle, 15 and with statues B appearing in the said niches.

A minor feature of the design is an annular band C encircling the bottle and passing over the fronts of the bases of the statues, and a second band D appears at the neck of 20 the bottle with diverging rods E leading to the upper ends of the statues.

I claim—

The design for a bottle as herein shown and described.

ALPHONS DRYFOOS.
